[57] CLAIM

The ornamental design for a chair, as shown and described.

DESCRIPTION

FIG. 1 is a perspective front view of a chair according to my design;

FIG. 2 is a side view of the chair according to my design; both sides of the chair being the same;

FIG. 3 is a rear view of the chair shown in FIG. 1;

FIG. 4 is a top view of the chair according to FIG. 1 but on a reduced scale, the schematically shown back thereof having the same appearance as in FIG. 1.

FIG. 5 is a bottom view of the chair according to FIG. 1 but on a reduced scale, the schematically shown back thereof having the same appearance as in FIG. 1.
